UNITED STATES PATENT OFFICE.

HERTHA AYRTON, OF HYDE PARK, LONDON, ENGLAND.

ARC-LIGHT CARBON.

1,261,891.

Specification of Letters Patent.

Patented Apr. 9, 1918.

Application filed September 28, 1914. Serial No. 863,894.

To all whom it may concern:

Be it known that I, HERTHA AYRTON, a subject of the King of Great Britain, residing at 41 Norfolk Square, Hyde Park, in the city and county of London, England, have invented certain new and useful Improvements in Arc-Light Carbons, of which the following is a specification.

This invention relates to negative arc light carbons and has for its object to provide an improved construction of such carbons.

I have previously published the results of certain experiments of blowing air and certain gases into the arc through holes bored through positive and negative carbons.

It has further been proposed to employ various constructions of hollow or tubular carbons where the walls of the tube were divided up to form a circle of individual carbons giving during burning a series of arcs, and in another case a tubular carbon was so arranged that the arc rested on one part of the annulus and by rotation of the carbon fresh parts of the annulus were presented to the arc and consumed.

After an extensive investigation I find that results far superior to anything hitherto produced both in steadiness of burning and regularity of consumption between positive and negative carbons and in general utility are obtained by the employment of a hollow negative carbon covered with a thin film of copper or other suitable material less combustible than the carbon. Suitable means are provided to prevent the passage of air through the hole to the arc.

I have previously proposed to employ a copper covering for another kind of carbon for searchlights and others have also proposed to use copper coverings but such coverings as hitherto proposed, have, so far as published, always been used for the purpose of increasing the conductivity of the carbon and thereby allowing of a reduction in diameter of the carbon or for causing the carbon to burn more slowly but so far as published it has never been proposed to regulate the rate of burning of a hollow carbon by varying the thickness of the copper coating. In the case of the present invention, the copper covering employed by me serves as a means for predetermining or adjusting the rate at which the hollow carbons will burn away.

The said copper covering forms a tightly adhering incombustible skin over the carbon which, while protecting the major portion of it from burning, always melts off and volatilizes at such a distance from the tip as to insure that the tip of the carbon shall be tapered to the right length for the carbon to burn away at the rate required.

I find that the thickness of the copper skin may be varied with advantage within certain limits.

The lower of these limits is determined by the thickness required to withstand the necessary handling and packing, the upper limit depends upon the thickness which will result in the tip of the carbon burning away with sufficient steepness to insure steadiness of the arc.

Within these limits quite a small variation in the thickness of the metallic skin makes a sufficient variation in the length of the carbon tip exposed to cause a considerable change in the rate of burning of the carbon. Increasing the thickness of the copper makes the carbon burn with a shorter blunter point and therefore more slowly, while diminishing the thickness of copper makes it burn with a longer and more tapering point and therefore more quickly.

I find that by choosing the right size of carbon and hole, and the right thickness of copper skin, it is always possible to obtain a hollow negative carbon that will burn steadily at substantially the same rate as any positive carbon suitable for the current and pressure employed, and, moreover, these results will be obtained in any of the various types of lamphouse usually employed.

Other metals besides copper may be employed to form the incombustible coating although copper has so far been found the most useful.

In a negative carbon made in accordance with the present invention and having a central hole it is also important that the said hole should be of such dimensions relatively to the size of the carbon, that during burning, the arc completely surrounds the hole, which is encircled by a flat surface from the outer edge of which the carbon tapers steeply away. When the hole is partially filled with a pencil of carbon the flat surface is not so apparent.

I find that with a negative carbon of 12

5 millimeters diameter coated with a film of copper about .04 millimeter in thickness and having a hole of 2 millimeters diameter leaving walls of 5 millimeters thickness, excellent results are obtained in an open direct current arc when used with a cored positive carbon and a current of 85 amperes.

10 What is usually employed in the ordinary cinematograph lamphouse is a negative carbon (not coppered) of 18 mm. diameter for the same current—85 amperes.

The cross sectional area of my new negative carbon is less than one half that of the ordinary negative carbon.

15 This advantage is maintained in all sizes but in varying degrees.

One great advantage arising from the comparatively small cross sectional area is that in use the shadow is lessened and there 20 are general advantages in the cost of manufacture and transport.

25 As is well understood the positive carbon has to be selected according to the amount of current and pressure. Any positive carbon may be used with my invention.

Referring to the accompanying drawings which show further examples of carbons made according to this invention:—

Figure 1 is a view in longitudinal section 30 of one form of carbon.

Fig. 2 is a view in longitudinal section of another form of carbon.

Fig. 3 is a view showing an example of the manner in which a pair of carbons burn 35 away in use.

Figs. 4 and 5 show modified constructions.

In the example shown in Fig. 1, the negative carbon a has a central hole b , which, however, does not extend completely, 40 through the carbon, one end a' of which is solid. The other end a'' of the carbon, where the arc is formed, is shown as slightly tapered and finished off obliquely, this being the shape which such a carbon assumes 45 in use when disposed at an angle in relation to the positive carbon for example as in Fig. 3. When the carbons are disposed in alignment the tip of the carbon will be flat instead of oblique. A thin film or coating c of copper is applied to the exterior surface.

In some cases a pencil of carbon may be located in the hole in such manner as to leave a suitable longitudinal space.

50 Fig. 2 shows an example of this kind of carbon and comprises the portion a having a central hole b closed at the end a' and a centrally disposed pencil of carbon d , of less diameter than the inside diameter of the said central hole b is located in the hole b . It will be seen by reference to the drawings, particularly Fig. 2, that the pencil d is not in surface engagement with the inner surface of the hollow tubular body a and 55 that there is considerable space between the

two. This carbon is coated with a film of copper or other metal or other suitable material less combustible than the carbon. The tip a'' of this carbon may be shaped as shown in the drawing or it may be shaped to any other appropriate form. If required the inner pencil of carbon may be coated with copper or other metal.

I am aware that it has hitherto been proposed to copper the cores of cored carbons. 75

Fig. 3 shows the oblique shape of the end of a negative carbon a , such as shown in Fig. 1, and the position which the oblique surface assumes relatively to the positive carbon p , in use when the said carbons are disposed in 80 the angular position shown. This view also shows the position normally occupied by the arc itself.

In the improved carbon the hole may in some cases be quite small relatively to the 85 thickness of the walls.

Any suitable means other than described may be employed for closing the hole to prevent the air passing therethrough to the arc, for example, the hole may be closed by 90 external means such as a part of the holder or a projection thereon.

Although I have fully herein set forth what I have found from experiment to give the beneficial results referred to, it is to be 95 understood that the claims are not to be restricted to the use of the particular thickness of copper mentioned as there may be circumstances in which a greater thickness of copper may be employed with advantage, 100 and my claims are to include a hollow carbon with any suitable thickness of copper coating or with a coating of other metal less combustible than the carbon and proportioned to give the specified effects and further if required, when a pencil of carbon is fitted into the hollow as in Fig. 2, said pencil may be covered with copper or other metal in the manner usual with cores. 105

According to a modification of the invention, shown in Fig. 4 as applied to a carbon constructed as in Fig. 1, the hole or holes of the hollow carbon are filled or charged as indicated at e with some substance which will burn away or melt so as to leave the tip 110 of the carbon or a suitable length near the tip hollow or recessed to such a distance as will give the results of a hollow carbon such as herein set forth.

As an example the filling or charging 120 may consist of silicate of soda in some convenient form although any other suitable material may be employed.

In this way the carbon may be said to be a cored carbon which will be hollow for the 125 whole or part of its length during burning or after being put into use.

When a pencil of carbon is employed in the hole as in Fig. 5 or holes it may be held in position by or the space between it and 130

the walls of the hole may be filled with material *e* which easily melts or burns away in the manner hereinbefore set forth.

What I claim and desire to secure by Letters Patent is:

1. An arc light carbon comprising a hollow tubular body open at the arc end and closed at the other end to prevent the passage of air, the carbon cylinder being of uniform thickness throughout that part which is to be burnt, said body having upon its outer surface a film of metal less combustible than the carbon and of a predetermined thickness for regulating the speed of burning of the said carbon.

2. An arc light carbon as claimed in claim 1 further characterized by a solid pencil of carbon of less diameter than the inside diameter of the said tubular body, and disposed therein.

3. An arc light carbon comprising a hollow tubular body having upon its outer surface a film of metal less combustible than the carbon and of a predetermined thickness for regulating the speed of burning of the said carbon, and a pencil of carbon of less diameter than the inside diameter of the said tubular body, and disposed therein,

the outer surface of the said pencil having a film of metal less combustible than the carbon of said pencil and of a predetermined thickness for regulating the speed of burning of the said carbon.

4. An arc light carbon as claimed in claim 1 characterized in that the hollow part is filled with a material adapted to be removed by the heat of the arc, so as to leave a suitable length of the carbon near the tip hollow to such a distance as will permit the carbon to burn in the manner of a hollow carbon.

5. An arc light carbon as claimed in claim 2 characterized in that the space between the pencil and outer wall is filled with material adapted to be removed so as to leave a suitable length of the carbon near the tip hollow to such a distance as will permit the carbon to burn in the manner of a hollow carbon.

In witness whereof, I have hereunto signed my name in the presence of two subscribing witnesses.

HERTHA AYRTON.
